UNITED STATES PATENT OFFICE.

WILHELM LORENZ, OF CARLSRUHE, BADEN, GERMANY.

MACHINE FOR PRESSING WADS OF WAX FOR USE IN FIRE-ARMS.

SPECIFICATION forming part of Letters Patent No. 247,832, dated October 4, 1881.

Application filed April 25, 1881. (No model.)

To all whom it may concern :

Be it known that I, WILHELM LORENZ, engineer and manufacturer, residing and doing business in Carlsruhe city, in the Grand Duchy 5 of Baden, German Empire, have invented a Machine for Pressing Wads of Wax for Use in Fire-Arms, of which the following is a specification.

The accompanying drawings form a part of 10 this specification, and represent what I consider the best manner of carrying out the invention.

Figure 1 is a side elevation. Fig. 2 is an end view. Fig. 3 is a section corresponding to Fig. 15 1, but with the vibrating parts in their extreme left position. Fig. 4 is a plan view. Fig. 5 is a vertical section.

Similar letters of reference indicate like parts in all the figures.

20 V is the upright, which is enlarged into a supporting frame-work at the top, where the various moving parts and stationary parts find bearings and supports.

X is a main shaft, sustained in the boxes V'. 25 On its end it bears the band-wheel R. By means of cams on this shaft the entire mechanism about to be described is operated.

a is the press-cylinder, in which the wads of 30 wax are pressed. The wax is fed up in long ropes through the feed-tube A, and is cut off and placed in the press-cylinder in the manner hereinafter to be described.

On the shaft X are the disks G H, with eccentric grooves in their circumference. In these 35 grooves short arms of the levers d f work. The lever d has the short arm e, which rocks a shaft, c, to which is attached the knife B, for cutting off the lengths of wax as it is fed up through the tube A, and the knock-off arm 40 F, which removes the wad from the end of the die after it has been pressed in the cylinder a. The lever f has a short arm, g, which rocks a shaft, c', to which is attached the lever C, which has a U-shaped cut in the free end. Into 45 this cut the lengths of wax are dropped when severed by the knife B. The lever C is then elevated by the rocking of the shaft c' until the wax it carries is brought into line with the axes of the stamps or dies, by which it is forced 50 into the press-cylinder a and formed.

On the shaft X is also carried the cams J J'. These operate upon the arms i h, which are movable backward and forward. These arms connect with levers L Q, pivoted at r and q. At the top of the levers the stamps D E are 55 mounted. At the bottom they are connected by the spring-rod M. By means of this the tops of the levers are spread apart and the stamps opened. But when the cams J J' overcome the action of the spring the stamps are 60 brought together and press the wax in the cylinder a.

On top of the framing a water-pot, N, is suspended, which drips water upon the tools to prevent the wax sticking to them.

65 By this machine wads are made of wax wire, (by which I mean continuous lengths of firm but sufficiently-plastic material, which may be beeswax or analogous material,) which is led to the same through the tube A in a continuous forward movement. At an appropriate moment the knife B cuts off a disk of a certain thickness, which is then elevated by the lever C to the center of the axis of the top and bottom stamps. The thickness of the disk to be 70 cut is regulated by a slower or faster shoving forward of the wax wire. The elevated wax disk is now taken up by the top stamp, D, and pushed into the press-cylinder a, to the orifice of which the bottom stamp, E, has moved to 75 prevent the disk from falling down. The top and bottom stamps move now with equal speed up to the center of the press-cylinder, where the pressing of the wad occurs, and the superfluous wax is led away by a side channel. 80 The bottom stamp, E, moves now quickly backward, while the top stamp, D, follows slowly and knocks out the finished wad. At this moment a lever, F, moves downward and knocks off the wad, in case the same should 85 stick to one or the other stamp. The fallen or knocked-off wads fall through the channel b, Fig. 2, into a collecting-box, P. The cutting off of the disks is done contemporary 90 with the knocking off of the wads, owing to the arrangement that the knife B and lever F are placed on the same shaft, c, which is moved by the eccentric disk G and the levers d and e. After this the eccentric disk H and the levers f and g cause the lifting-up of the previ- 95 100

ously-cut-off disk, and then the stamps D and E are put in motion, as above described, by the eccentrics J and J', acting by means of the rods h and i upon the levers Q and L, which swing around the points q and r. The rollers K serve to reduce the friction, and the same, with the rods i and h, are pressed continuously against the eccentrics by means of the spring M.

The water-box N serves by drops to moisten the tools. The waste-water flows away through the pipe O into the box V. The machine is started by the loose pulley R, by means of the coupling S and the hand-lever T. The whole is placed on the pillar U, leaving

from all sides free access to the machine. I claim as my invention—
1. In a machine for forming wads of wax, the combination of the press-cylinder a and the horizontally-moving stamps E D, substantially as set forth.

2. The combination of the knife B and lever

C with the cylinder a and stamps D E, substantially as set forth.

3. In a wax-wad-forming machine, the combination of the cams J J', arms i h, pivoted levers L Q, and stamps E D, substantially as set forth.

4. The combination of the cams J J', arms i h, pivoted levers L Q, spring-rod M, and stamps E D, substantially as set forth.

5. The combination of the cam-grooved disks G H, connecting-levers, and rocking centers, with the knife B, knock-off lever F, and lever C, substantially as set forth.

In testimony whereof I have hereunto set my hand at Berlin, Prussia, this 1st day of February, 1881, in the presence of two subscribing witnesses.

WILHELM LORENZ.
